UNITED STATES PATENT OFFICE.

RUBIN ROTHMAN, OF BROOKLYN, NEW YORK.

METHOD OF SEALING BOTTLES.

1,092,399.

Specification of Letters Patent.

Patented Apr. 7, 1914.

Application filed September 20, 1913. Serial No. 790,858.

To all whom it may concern:

Be it known that I, RUBIN ROTHMAN, a subject of the Emperor of Russia, and resident of the borough of Brooklyn, in the county of Kings and State of New York, have invented certain new and useful Improvements in Methods of Sealing Bottles, of which the following is a specification.

This invention has for its object to provide an improved process for securely retaining a closure in the form of a cap or hood on the top of a bottle or jar, and is especially designed for the form of wide-mouth bottles or jars usually employed for the delivery of milk to customers; and it consists, essentially, in providing a form of wire ring with a helix at one end, through which the other end of the wire is passed and drawn taut around the hood or cap below the bead on the bottle neck, and thereupon the engaging end portions of the wire ring are deflected to cause them to be securely locked together.

In the accompanying drawing illustrating embodiments of my invention, Figure 1 shows a bottle with the closure applied. Fig. 2 shows enlarged the wire ring in the open position. Fig. 3 is a similar view, with the end portions of the wire in clamped position; Fig. 4 is a view enlarged of the end portions of a ring in the locked position, with the extremity of the ring deflected, and Fig. 5 shows the helix.

In Fig. 1 of the drawings is shown a bottle 6 of the wide-mouth form, having a bead 7 on the outside of the neck at the top. A cap or hood 8 of any preferred material, preferably of a comparatively stiff paper, is placed on top of the bottle, and has its sides extending down a short distance beyond the bead 7 of the bottle. Around this lower portion of the cap 8 is placed a wire ring, denoted generally by 9, whose end portions are provided with means for contracting the ring to press the edges of the cap tightly against the bottle neck just below the bead on the bottle, and which end portions can be locked together to securely retain the cap in this position.

One end portion of the ring 9 is provided with a helix 10, as shown separately in Fig. 5, of a size to permit the other end portion 12 of the ring 9 to pass through the axis of the helix; and this end portion 12 is so inserted before the ring is placed over the hood or cap on the bottle, the ring before applica-

tion being large enough to be passed down over the hood around the bead 7. This ring is now grasped by suitable means, and the extending end 12 is drawn out or through the helix 10, whereby the size or diameter of the ring will be contracted, and will draw the lower edges of the hood inwardly against the bottle neck below the bead 7, as indicated in Fig. 1. Of course this can be done with simple hand tools, such as pliers or the like, or else an automatic machine could be employed for such purpose.

For the purpose of securing the portion 12 of the ring that is surrounded by the helix 10, this portion of the ring is suitably compressed, such as by squeezing it with a pair of pliers, or any form of jaws or the like, that will bend the wire portion 12 inside of the helix to an irregular shape, most likely in the form of a sinusoid or wave; and at the same time the helix will be somewhat compressed or distorted out of a regular form or shape. This it will be readily understood will lock the two engaging end portions of the ring 9 together, and prevent withdrawal of the end portion 12, or any enlargement of the ring. The drawing of the end 12 through the helix before locking the two portions together, will serve to clamp the edges of the cap or hood 8 tightly against the bottle neck below the bead on the bottle, and then the locking operation will insure the retention of the cap on top of the bottle, thus forming a practically fluid-tight closure for the bottle. Preferably the end portion 12 of the wire ring that now projects beyond the helix 10, in the locked position of the helix, can be severed by clippers, or any desired form of cutting means. This end portion 12 of the wire, can be severed so as to leave a short end portion beyond the helix, that can be deflected laterally as shown at 13 in Fig. 4, that will assist in the locking operation, as it would tend to prevent withdrawal of the end portion of the wire back through the helix 10. And in fact, this laterally bent portion might itself serve as a locking means to prevent withdrawal of the wire, and serve to lock the two end portions of the wire ring in position to clamp the hood against the bottle neck. In the operation of cutting off the extending end portion 12, the nippers or other cutting means could be caused at the same time to produce the described lateral bending of the remaining end portion of the

wire 12; whereby the operation of severing the free extension would at the same time effect the locking together of the end portion of the wire.

5 Having thus described my invention, what I claim is:

1. The herein described method of securing a cap on a bottle that is provided with a bead at the top by means of a circular wire 10 ring, consisting in placing around the cap below the bead a circular wire ring provided with a helix at one end portion with the other end portion of the wire projecting through such helix, thereupon drawing said 15 free end through the helix to contact the ring and press the cap tightly against the bottle neck, and thereupon causing the helix to be closed upon the said inner wire portion whereby to deflect such inner portion and 20 lock the two end portions of the ring together and secure the cap upon the bottle.
2. The herein described method of securing a cap on a bottle that is provided with a bead at the top by means of a circular wire 25 ring, consisting in placing around the cap below the bead a circular wire ring provided with a helix at one end portion with the other end portion of the wire projecting

through such helix, thereupon drawing said free end through the helix to contract the 30 ring and press the cap tightly against the bottle neck, and thereupon causing the helix to be closed upon the said inner wire portion whereby to deflect such inner portion and 35 lock the two end portions of the ring together and secure the cap upon the bottle, and also causing the inner wire to have its extremity bent laterally at the end portion of the helix.

3. The herein described method of securing a cap on a bottle that is provided with a bead at the top by means of a circular wire 40 ring, consisting in placing around the cap below the bead a circular wire ring provided with a helix at one end portion with the 45 other end portion of the wire projecting through such helix, thereupon drawing said free end through the helix to contract the ring and press the cap tightly against the bottle neck, and thereupon compressing the 50 helix and free end into interlocking engagement.

RUBIN ROTHMAN.
